Primary Examiner — Selina Sikder(74) *Attorney, Agent, or Firm* — Lee & Hayes, P.C.(57) **CLAIM**

The ornamental design for a door interface system having an animated visual indicator, as shown and described.

DESCRIPTION

FIG. 1 is a top, front, right-side perspective view of a vehicle with a door interface system;

FIG. 2 is an enlarged perspective view of a relevant portion of features in the circle marked 2 in FIG. 1; and,

FIG. 3 is a front view of the enlarged view of FIG. 2.

The broken lines immediately adjacent to the shaded surfaces represent boundaries of the claim and form no part thereof; all other broken lines depict unclaimed environmental subject matter and form no part of the claim.
